Group, LLC

CLAIM

The ornamental design for a display screen or portion thereof with graphical user interface as shown and described.

DESCRIPTION

The sole FIGURE shows a display screen or portion thereof with graphical user interface showing our new design.
Shading represents tonal contrast.

The peripheral dashed broken lines illustrate a display screen or portion thereof, and form no part of the claimed design. The interior dashed broken lines form no part of the claimed design.

1 Claim, 1 Drawing Sheet
